UNITED STATES PATENT OFFICE.

HERMANN W. VOGES, OF SPRINGFIELD, MASSACHUSETTS.

MICROMETER-CALIPERS.

1,244,263.

Specification of Letters Patent. Patented Oct. 23, 1917.

Application filed June 21, 1916. Serial No. 105,027.

To all whom it may concern:

Be it known that I, HERMANN W. VOGES, a citizen of the United States of America, and resident of Springfield, in the county of 5 Hampden and State of Massachusetts, have invented certain new and useful Improvements in Micrometer-Calipers, of which the following is a full, clear, and exact description.

10 This invention relates to a micrometer caliper having interchangeable frames of different sizes so that by having one micrometer barrel and a plurality or series of different sized frames with which the barrel member 15 may be detachably connected, one may have, at greatly lessened expense than heretofore, instruments of different measuring ranges.

The object of the invention is to improve the caliper device especially in respect to the 20 means of detachable connection between the barrel portion and the bow or frame portion to the end of securing accuracy as regards the relations of the parts, convenience of operation, reliability, simplicity and inexpensiveness of construction.

25 The invention is described in conjunction with the accompanying drawings and is set forth in the claims.

In the drawings:

30 Figure 1 is a side view showing the caliper comprising interchangeable parts in their assembled relations.

Fig. 2 is a plan view and partial horizontal section as taken on line 2-2, Fig. 1.

35 Fig. 3 is a side view of one of the frames or bows of a different size from the one shown in Fig. 1, and understood as being interchangeable therewith.

In the drawings, A represents the barrel 40 portion of the caliper, which, as may be sufficiently said, is of any of the usual or standard constructions; and this barrel portion of the caliper is provided with a tang or projection B, which extends from the barrel 45 angularly to the axis thereof, the outer edge portion a of which is of reversely beveled or V-shape, as shown in Fig. 2.

CC represent interchangeable separately formed bow-shaped yokes or frames, the one 50 in Fig. 1 being considerably shorter than the one represented in Fig. 3.

Each of the frames C, to be provided is identically formed at its end portion opposite the anvil member b with a parallel 55 edged slideway or channel d for the engage-

ment therein of the tang B of the barrel member.

As here represented the channel d is open to the front face of the frame, and the outer wall or boundary of the channel is undercut as represented at f for the interlocking engagement therein of the angularly formed edge of the tang.

The frame has a sector shaped recess g within its front face adjacent an opening 65 to the inner side wall of the channel, and the arc shaped wall of this recess is formed with an undercut bevel h.

D represents a member, which has the form of a disk or circular block mounted on 70 the front of the tang, on the pivot screw i, and capable of rotative movement.

This member D is made at its inner portion with a cam m, which advantageously 75 may be of eccentric form or approximately such.

This cam m is accommodated in a shallow socket or rabbet o within the front face 80 of the tang and which socket opens to one edge of the tang.

The edge j of the cam is shown as of angular form or beveled in a direction so that when turned to bind the tang in the channel of the frame, the cam will also acquire an interlocking engagement with 85 the undercut wall forming the boundary of the sector shaped niche or recess g.

The said recess g in conjunction with the 90 rotative binding cam serves as means for properly positioning the tang in its arrangement on the frame so that the axis of the barrel member will be coincident with the axis of the anvil.

The cam provided member D may be rotated by being grasped between the thumb 95 and finger or, as shown, the member D is provided with a small lever handle t.

As the greatest expense in the manufacture of a micrometer caliper is in the construction of the portions comprised in the 100 barrel, it will be readily understood that by providing one micrometer barrel having the tang and a number of frames of different sizes, all caliper measuring requirements are readily and cheaply provided for.

I claim:

1. The combination with the barrel portion of a micrometer caliper provided with a tang extended from the barrel portion 110 angularly to the axis of the latter, of a

- separately formed bow shaped yoke or frame having in one end portion thereof a channel opening to the face of the frame, and a member pivotally mounted on the tang and provided with a cam which under the rotative movement of the pivoted member is operable to engage one wall of the channel and bind the tang and the portion of the instrument carried thereby firmly to the frame.
2. The combination with the barrel portion of a caliper provided with a tang extended from the barrel portion angularly to the axis of the latter, of a separately formed bow shaped yoke or frame having in one end portion thereof a channel which opens to the face of the frame and one side wall of which is undercut, and a member rotatively mounted on the tang, and provided with a cam member for a binding engagement against one side wall of the channel, one edge portion of the tang being of beveled form for engagement with such undercut wall.
3. The combination with the barrel por-

tion of a micrometer caliper provided with a tang extended from the barrel portion angularly to the axis of the latter, one edge portion of which tang is of beveled form, of a frame member or yoke having at one end portion thereof a facewise opening channel, one side wall of which is undercut, and said frame having a sector shaped recess within its face adjacent and opening to the other side wall of the channel, the arc shaped wall of said recess being undercut, and a member pivoted on the tang and having a cam the edge of which is beveled and operable under the rotation of said pivoted member to both bind the tang in the channeled frame and to secure an interlock between the beveled edge portion of the cam and the undercut wall of the sector shaped recess.

Signed by me at Springfield, Mass., in presence of two subscribing witnesses.

HERMANN W. VOGES.
